RAILWAY SWITCH

Application filed May 31, 1929. Serial No. 367,451.

This invention relates to switches and operating means therefor and more particularly to a railway switch having operating means adapted to be actuated by a train-carried element and by means of which switch points may be moved into position to allow a train to move along the main track past a side track and the switch points returned to a normal position to guide another train onto the side track after the first train has entirely passed over the switch points.

One object of the invention is to so construct the switch operating means that it may be easily applied to trackage of a conventional construction with its operating means at one side of the track and extending from the switch points for quite a distance along the track.

Another object of the invention is to provide the actuating means with levers so constructed that when they are engaged by an abutment arm extending from a portion of an engine or car of a train and moved in an operative direction their movement may be checked and breakage which may occur from a violent throw of a lever prevented.

Another object of the invention is to provide the actuating mechanism with shock absorbing means which will serve to absorb strains which occur during movement of the operating means and prevent breakage.

Another object of the invention is to provide an improved type of abutment arm adapted to be mounted upon an engine or car and moved into and out of position for engagement with the levers of the track mechanism.

Another object of the invention is to provide switch operating means which is strong and durable and simple in its construction.

The invention is illustrated in the accompanying drawings, wherein

Figure 1 is a top plan view of a section of trackage showing the improved operating means connected with movable switch points of the trackage,

Fig. 2 is a side elevation of the structure shown in Fig. 1,

Fig. 3 is a transverse sectional view taken on the line 3—3 of Fig. 1,

Fig. 4 is a view in side elevation showing the manner in which a lever is moved by an abutment arm carried by an engine,

Fig. 5 is a perspective view of the train appliance, and

Fig. 6 is a vertical sectional view taken on the line 6—6 of Fig. 5.

The trackage shown in Fig. 1 consists of a main track, indicated in general by the numeral 1, a side track 2 and switch points 3

which are pivotally mounted, as shown at 4, for horizontal swinging movement from a position in which they will guide a train moving along the main track onto the side

track to an adjusted position in which they will cause the train to continue along the main track past the side track. In order to connect the switch points and cause them to move together, there has been provided a tie

bar 5 formed of companion strips 6 disposed one upon the other with their end portions

projecting beneath rails of the track, as shown in Fig. 3. These strips 6 which are formed of steel or other strong metal have

a number of openings formed through them which are adapted to register and through

these openings are passed securing bolts 7 and

8, the bolt 8 being located between the bolts

7. Fasteners, such as the bolts 9, connect the

switch points with the extended end portions

of the strip 6 and bushings 10 are fitted about

the bolts 9 between the extended ends of the

strips and under faces of the switch points

so that the strips may be firmly secured to the

switch points but at the same time retained

in slightly spaced relation to them. It will

thus be seen that the tie bar may be adjusted

to accommodate itself to the width of a track

and be firmly secured to switch points so

that the switch points will be retained in

proper spaced relation to each other and be caused to move together.

A draw bar 11 extends longitudinally beneath the tie rod or bar 5 and this draw bar has its inner end portion formed into a stem 12 which is threaded and carries nuts 13. The stem passes through an opening formed in a depending arm of a bracket 14 which is firmly secured to the tie bar 5 by the bolt 8 and between the bracket 14 and the nuts 13

are disposed springs 15 which are held under compression by the nuts. By this arrangement the tie bar and the switch points may be moved transversely of the track to guide a train onto the side track or cause it to continue along the main track by moving the draw bar longitudinally and the springs will prevent breakage due to over strain. The outer end portion of the draw bar is bent upwardly, as shown at 15, and then outwardly, as shown at 16, to form a handle and to this handle is secured a cleat 17 between which and the handle 16 is connected the arm 18 of a bell crank lever 19. This bell crank lever is pivotally mounted upon a post 20 rising from a base plate 21 spiked or otherwise firmly secured upon end portions of ties at one side of the track. It will be readily understood that by swinging the bell crank lever on its post movement may be imparted to the draw bar and the switch points shifted from one position to another.

Clevises 22 and 23 are pivotally connected with the outer end of the bell crank lever by a pin or bolt 24 and these clevises are preferably formed with a number of openings so that they may be adjusted longitudinally of each other before the pin is passed through them and through the lever. Rods 25 and 26 have threaded ends passed through openings in the clevises where they are secured by nuts 27 and 28 so that they may be adjusted and these rods extend longitudinally of the track. The rod 25 carries at its other end a similar clevis 29 which is secured thereon by securing nuts 30 similar to the nuts 27 and 28, and this clevis 29 is pivotally connected with the lower end of a lever 31 which is pivotally mounted upon a shaft 32 carried by brackets 33 extending upwardly from a base plate 34 spiked or otherwise rigidly secured upon the end portions of ties at one side of the track. It will be readily seen that by moving the lever, longitudinal movement may be imparted to the rod 25 and since this rod is connected with the bell crank lever the switch points will be adjusted. An arm 35 is carried by the lever 31 and extends upwardly therefrom so that, when a train is approaching the switch, an abutment carried by the train may if set in an operative position strike the arm 35 and cause the lever to be swung forwardly and draw upon the rod 25 to swing the switch points out of the position shown in Fig. 1 in which they will guide a train upon the side track to an adjusted position in which they will cause the train to continue along the main track. When the lever is swung forwardly by the train abutment striking the arm 35, the upper end of the lever 31 will rest upon the abutment until the train has moved forwardly a sufficient distance to move the abutment out of engagement with the arm and lever. The lever will then continue its downward movement in order to fully set the

switch points. By this arrangement movement of the lever will be temporarily checked by engagement of the lever with the abutment and, therefore, a violent throw of the lever will be prevented and breakage due to a violent throw of the lever prevented.

The rod 26 which extends along the track in an opposite direction to the rod 25 need not necessarily be as long as the rod 25 although it may be of the same length and this rod is pivotally connected with a metal block 36 pivotally mounted by a shaft 37, which shaft is carried by brackets 38 secured upon a plate 39 in depending relation thereto at opposite sides of an opening 39' formed in the plate. This plate 39 is spiked or otherwise firmly secured to the end portions of ties at one side of the main track and against the inner face of the block in a recess formed therein is secured a lever 40 which projects upwardly from the block. This lever is firmly held in its proper position relative to the block due to its being secured in a recess formed therein and it carries an arm 41 which corresponds to the arm 35 of the lever 31. The block 36 constitutes a balance weight so that, when the lever 31 is swung forwardly, the weight will cause movement of the switch points to be continued when the train abutment moves out of engagement with the lever 31 and insure proper setting of the switch points. From an inspection of Fig. 2, it will be readily seen that, when the lever 31 is thrown forward, pull is exerted through the rod 26 to swing the lever 40 upwardly and, therefore, the lever 40 will assume a position corresponding to the position of the lever 31 when the lever is swung forwardly to the position indicated by dotted lines in Fig. 4. Therefore, after a train has passed over the switch points the abutment carried by the train may strike the arm 41 of the lever 40 and by exerting pull upon the rod 26 turn the bell crank lever about its post to return the switch points to the position shown in Fig. 1. Of course, if a train is to enter the side track instead of continuing along the main track, the abutment carried by the train will be left in an inoperative position so that the train may pass the lever 31 without actuating the switch operating mechanism.

While any suitable means may be provided upon a train for engaging the arms of the two levers, we prefer to use abutment means constructed, as shown in Figs. 4 and 5. Referring to Fig. 5, it will be seen that the abutment consists of an arm 42 formed of steel or other strong metal and this arm is firmly fixed upon a shaft 43 journaled in openings formed in the outstanding arms 44 of a pair of bearing brackets 45 which brackets are riveted or otherwise firmly secured upon a plate 46 having openings 47 formed therein so that it may be secured in a vertical position against one side of an engine. The abutment will be

so located upon the engine that when the shaft 43 is rotated to swing the arm upwardly and outwardly it will project in a horizontal plane at such a distance above the track that as the train moves along the track it may have contacting engagement with the arms of the two levers, as shown in Fig. 4, in order to swing the levers forwardly and be engaged by the upper ends of these levers in order to check forward movement thereof until it moves forwardly out of position to be engaged by the levers. A strip 48 extends between the arms of the bearing brackets in order to limit upward movement of the arm, as shown in Fig. 6, and in order to rotate the shaft 43 for adjustment of the abutment arm, there have been provided actuating rods 49 which extend from the same towards the front and rear ends of the engine and have their free ends bent to form handles 50, one of which will be disposed where it may be easily reached by the engineer or fireman while seated in the cab of the engine and the other of which will be accessible to a member of the engine crew who may be riding near the front of the engine. A similar abutment may be mounted upon the rear car of a train, such as the caboose of a freight train, so that trainmen riding in the rear car may move it to an operative position and allow the switch to be returned to its normal position from an abutment at the rear end of a train instead of upon the engine after the rear car has passed over the switch. By this arrangement there will be no danger of a switch being returned to the position shown in Fig. 1 before all of the cars of a train had passed the switch at the entrance to a side track. We have, therefore, provided switch control means whereby a switch at the entrance to a side track may be adjusted in order to control movement of a train without it being necessary for the train to stop and a trainman leave the train and then again board the train after the switch has been set.

Having thus described the invention, we claim:

1. In a railway switch structure, trackage including a movable switch point, a draw bar connected with said switch point and projecting from one side of the trackage, and actuating means for said draw bar including levers spaced from each other longitudinally of the track with one lever in advance of and the other beyond the switch, each lever being pivotally mounted for swinging vertically from a lowered to a raised position and having a side arm rigid with the lever and extending diagonally from one side of the lever in diverging relation to the free upper end of the lever whereby the lever may be moved by a train element striking the arm and movement of the lever checked by the lever striking the train element.
2. In a railway switch structure, trackage including a movable switch point, a draw bar connected with said switch point and projecting from one side of the trackage, an element pivotally mounted for movement in a horizontal plane and having an arm pivotally connected to said draw bar to move the draw bar longitudinally when the element is moved and a second arm extending transversely of the first arm, rods pivotally connected to the second arm and extending transversely therefrom longitudinally of the track at one side thereof in opposite directions, levers pivotally mounted for vertical movement having said rods connected thereto and one lever moving upwardly when the other is moved downwardly, and a side arm rigidly secured to each lever and extending diagonally therefrom in diverging relation to the upper end of the lever.
3. In a railway switch structure, trackage including movable switch points, a cross bar connecting said switch points, a draw bar connected with said cross bar and projecting from one side of the trackage, a bell crank lever having one arm pivoted to said draw bar, rods pivotally connected at their inner ends with the other arm of said lever and extending in opposite directions therefrom longitudinally of the track, operating levers pivotally mounted for vertically swinging movement and having the outer ends of said rods pivotally connected therewith with one rod connected below the pivotal mounting of its companion lever and the other connected with its companion lever above the pivotal mounting thereof whereby one lever moves upwardly while the other swings downwardly, and an arm rigidly secured to each lever and extending diagonally therefrom in diverging relation to the free end of the lever.
4. In a railway switch structure, trackage including movable switch points, a cross bar connecting said switch points, a draw bar connected with said cross bar and projecting from one side of the trackage, a bell crank lever having one arm pivoted to said draw bar, clevises pivotally connected with the other arm of said lever and extending in opposite directions therefrom longitudinally of the track, rods extending longitudinally of the track and having adjacent ends connected with said clevises, operating levers pivotally mounted and having said rods connected thereto, a weight associated with one lever, and side arms projecting from said levers and extending diagonally of the levers in diverging relation to the free ends of the levers.
5. In a railway switch structure, trackage including movable switch points, a cross bar connecting said points, a draw bar connected to said cross bar and extending beneath the same with one end projecting from one side of the track, a base plate secured upon ties of the track, a bell crank lever pivotally connected to the base plate and having one arm pivoted to the draw bar to move the draw bar longitudinally when the lever is moved and a second arm extending transversely of the first arm, rods pivotally connected to the second arm and extending transversely therefrom longitudinally of the track at one side thereof in opposite directions, levers pivotally mounted for vertical movement having said rods connected thereto and one lever moving upwardly when the other is moved downwardly, and a side arm rigidly secured to each lever and extending diagonally therefrom in diverging relation to the upper end of the lever.

- mounted upon said plate with one arm connected to the outer end of said draw bar, rods pivoted to the other arm of said bell crank lever and extending in opposite direction therefrom longitudinally of the track, base plates secured upon ties of the track adjacent the ends of said rods, bearing brackets carried by the last-mentioned base plates, shafts carried by said bearing brackets, a lever carried by one shaft and extending above and below the same with its lower end pivoted to one rod, a weight carried by the other shaft, a lever firmly secured against a side of said weight and extending upwardly therefrom, the other rod being pivoted to the upper portion of said weight, and arms extending transversely from the operating levers in diverging relation to the free ends thereof.
6. In a railway switch structure, trackage including movable switch points, a cross bar connecting said switch points and consisting of strips adjustably secured in overlapped relation to each other with end portions projecting and secured to the switch points, a bracket secured to said cross bar and depending therefrom intermediate its length, a draw bar extending beneath said cross bar with one end projecting from the track at one side thereof and its inner end portion slidably passed through the bracket, abutment nuts upon said draw bar in spaced relation to opposite sides of the bracket, springs between said bracket and nuts, a bell crank lever pivotally mounted at one side of the track and having an arm pivoted to the outer end of said draw bar, rods connected to the other arm of the bell crank lever and extending therefrom longitudinally of the track in opposite directions, and operating means connected with said rods.

In testimony whereof we affix our signatures.
